DISPLAY PIECE FOR BOTTLES

Cecil P. Kahmann, San Carlos, Calif., assignor to Schenley
Industries, Inc., New York, N. Y., a corporation of Delaware

Application December 12, 1955, Serial No. 39,287

Term of patent 14 years

(Cl. D80—9)

The side of the display piece for bottles opposite that shown in Figure 1 is the same as the latter.

I claim:

The ornamental design for a display piece for bottles, as shown and described.
